UNITED STATES PATENT OFFICE

CHARLES KEET HUTHSING, OF ST. LOUIS COUNTY, MISSOURI

FIRE EXTINGUISHER

Application filed October 27, 1930. Serial No. 491,410.

My invention relates to a fire extinguisher of the chemical type and particularly to means for supporting the acid container in the upper portion of such extinguisher.

5 The object of my invention is to provide an acid container cage for fire extinguishers which may be easily and cheaply manufactured and which will at the same time be both light in weight and rigid in construction.

10 In the accompanying drawing, which illustrates one form of fire extinguisher made in accordance with my invention, Figure 1 is a vertical section through the upper part of the extinguisher; Figure 2 is a side elevation 15 of the cage; Figure 3 is a view similar to Figure 2 but taken at right angles thereto; Figure 4 is a top plan view of the cage; and Figure 5 is a detail view showing the cage supporting lugs on the collar surrounding 20 the charging opening.

Referring first to Figure 1, 6 indicates the body of a fire extinguisher having the usual dome 7 provided with the charging opening surrounded by an externally threaded collar 8. The charging opening is closed by means 25 of a cap 9 engaging with the collar 8 and provided with a hand wheel 10 for rotating the cap and for manipulating the extinguisher. A rubber gasket 11 serves to secure a tight 30 joint between the cap and collar. On the interior of the collar are supporting lugs 12, preferably four in number, as shown in Figure 5.

Adapted to engage with the lugs 12 are a 35 pair of supporting members each substantially semicircular in form and comprising a vertical flange 13 and a horizontal flange 14. These supporting members are secured to the upper ends of the cage arms, preferably by 40 means of rivets 15. The cage body is formed from a single rectangular sheet of metal somewhat longer than twice the height of the container 16 (shown in dotted lines in Figure 1), and slightly wider than the diameter 45 of the container. This sheet of metal is formed, by suitable dies, into the shape shown comprising a pair of curved arms 17 and a bottom 18. The interior diameter of the cage should be equal to or but slightly greater 50 than the diameter of the container. Owing

to the fact that the sheet from which the cage body is formed is wider than the diameter of the container, a pair of reinforcing flanges 19 will be produced, forming bridges extending between the arms and thus providing a 55 very rigid bottom. Formed in the bottom is an annular bead 20 which not only gives additional strength but also provides gripping means for the sheet as it is forced through the forming die. Formed in each arm of the 60 cage are a pair of vertical slits, the intermediate portions of the metal being forced inwardly to provide a stop 21 for engagement with the shoulder of the acid container.

Owing to the configuration of the cage it 65 may be formed of thin metal so as to be both lighter and stronger than the forms of cage in common use. The use of the reinforcing flanges 19 produces a rigid bottom but permits the upper ends of the arms 17 to be 70 sprung apart sufficiently to allow of the insertion or removal of the acid container when the cage is withdrawn from the extinguisher.

Having fully described my invention, what 75 I claim as new and desire to secure by Letters Patent of the United States is:

In a device of the class described, the combination with a fire extinguisher provided with a charging opening, of a container support extending into the extinguisher through said opening, said support including a bottom plate and an integral side wall perpendicular to the bottom wall throughout its length, said side wall including a pair of 80 arms arcuate in cross section, each of said arms being provided intermediate its length with a pair of vertical slits, the material between said slits being bent inwardly to provide a shoulder stop for the container.

In testimony whereof, I hereunto affix my 85 signature, this 23rd day of October, 1930.

CHARLES KEET HUTHSING.
